UNITED STATES PATENT OFFICE.

HENRY GARNER AND JAMES PARKER GARNER, OF BIRMINGHAM, ENGLAND.

TRANSPARENT PANEL.

Application filed October 3, 1922. Serial No. 592,170.

To all whom it may concern:

Be it known that we, HENRY GARNER and JAMES PARKER GARNER, both subjects of the King of Great Britain, and residents of 5 "Avalon," Wake Green Road, Moseley, Birmingham, in the county of Warwick, England, and 37 Forest Road, Moseley, aforesaid, respectively, have invented certain new and useful Improvements in Trans- 10 parent Panels; and we do hereby declare the following to be a full, clear, and exact description of the same.

This invention relates to transparent panels and is intended primarily for sliding 15 windows for use upon vehicles.

One object of the present invention is to provide an improved transparent panel which will be lighter in weight and which will be less likely to be broken than those 20 at present in use.

A further object of the present invention is to provide a transparent panel which will have the necessary degree of transparency but which will be sufficiently stiff to with- 25 stand wind pressure without distortion.

A further object of the present invention is to provide a transparent panel which will be resilient, i. e., which will have sufficient flexibility to allow of it bending so 30 that it can slide in curved guides but which will have sufficient stiffness as will cause it automatically to regain a flat formation when released from the curved guides.

A further object of the present invention is to provide an improved transparent panel which will be sufficiently stiff to enable it to be pushed along guides from one end without distortion.

A further object of the present invention is to provide an improved transparent panel which will have a maximum degree of transparency and light transmitting qualities.

It is proposed to construct our improved transparent panel by taking a sheet of comparatively flexible transparent material such as celluloid and to thicken the edges of the panel to obtain the necessary degree of resiliency or stiffness.

A further object of the present invention is to construct the panel so that the main sheet of material will not buckle or the stiffening strips, if made separately, come loose from the main sheet when the temperature of the panel is raised. Under some circumstances the thickening pieces employed at the edges may require to expand more or

less than the main sheet when the temperature is raised.

For thickening the edges of the panel we use material which has substantially the same co-efficient of expansion due to differences of temperature as the main sheet. In addition, particularly at the end edges, we may use strips of material having a different co-efficient of expansion from the main sheet but which strips are mounted upon the main sheet in such manner that the necessary relative expansion can take place.

Instead of forming the thickened edges of the main sheet of separate strips secured 70 to the main sheet of material the thickened edges may be made integral therewith by forming them in the process of manufacture of the sheet by means of pressing or other operations.

Referring to the drawings:—

Figure 1 is a view in side elevation showing one form of sliding window.

Figure 2 is a sectional plan view of same.

Figure 3 is a sectional view in end elevation of the window.

Figure 4 is a sectional end view of a modified form of sliding window.

Figure 5 is a side view partly in section of the window illustrated by Figure 4.

Figure 6 is a sectional end view showing a further modification of the sliding window.

Figure 7 is a sectional side view of the window shown in Figure 6.

In the construction illustrated in Figures 1, 2 and 3 the window consists of a thin sheet 80 of transparent flexible material such as celluloid thickened at its sliding edges by strips of celluloid 81 and 82 which are secured to the sheet 80 by a suitable cement and by the application of pressure. Other means for securing these strips may be employed if desired and in some cases a transparent flexible window of the general form shown may be constructed by making the thickened edges integral with the sheet 80. This may be done in the manufacture of the sheet by pressure means.

As will be seen from Figures 1, 2 and 3 the sliding edges of the sheet 80 are thickened on one side by single strips 81 and upon the other side by two strips 82. At the top and bottom or transverse edges however, the strip 81 and one of the strips 82 are omitted and metal channels 83 are mounted upon the edges of the window for

the purpose of taking the wear. The whole of the edges of the window are thus of the same thickness.

In the construction shown in Figures 1, 5 2 and 3 the transverse and sliding edges of the window are shown as being thickened with strips of celluloid or similar material to the material of the main sheet of the window. This construction is suggested 10 mainly because it has been found desirable to employ for thickening the edges of the window, strips having the same or substantially the same co-efficient of expansion due to variation in temperature as the main 15 sheet of the window itself. If the co-efficients of expansion of the materials used in the window construction were different, there would be danger of buckling or even of the thickening strips becoming loose. For 20 this reason the channels 83 may be left unsecured to the window, retaining their position thereon merely by reason of a friction tight fit thereon.

In constructing a sliding flexible transparent window of celluloid or analogous material it is necessary to select a comparatively thin sheet in order to obtain a maximum of transparency. Such sheets however, may not be sufficiently stiff to give good 25 results as they may buckle under wind pressure. Hence the suggestion that the edges should be thickened.

In addition to thickening the edges of the window with strips of the same or similar 30 material to the window itself, they may be stiffened with metal or other rods or strips. As however, the co-efficient of expansion due to variations of temperature of metal and the material of which the window is made may 35 be very different, any of the constructions or any equivalent construction to those shown in Figures 4 to 7 may be employed.

In the construction shown in Figures 4 and 5 the main panel 23 of the window has 40 its transverse edges stiffened by metal members. At the top a metal rod 24 is employed. This metal rod is not actually fastened to the window but is free or floats in a pocket formed at the top of the window by a 45 moulded or bent strip of celluloid 25 or like material which is cemented or otherwise secured to the upper edge of the main panel. The pocket 26 which is formed to accommodate the rod 24 is longer than the rod 24 50 as shown clearly in Figure 5. The pocket 26 has its ends closed by members 27 which are secured in the ends of the pocket.

At its lower edge this window is stiffened 55 by a metal rod 28 of substantially rectangular form which floats freely in a pocket 29 which is formed by a moulded strip 30 of

celluloid or like material cemented to the lower edge of the window. The strip 30 has its lower part formed of channel section having two flanges the edges 31 of which are turned inwardly to accommodate a strip or rod 32 which forms a buffer.

It will be understood that the sliding edges of the window may be reinforced by strips of metal of flat section if desired, but if such strips are employed upon the window they are associated with the window in such manner that they are free to expand to a greater or less degree than the window itself under the influence of increases of 75 temperature.

Another construction is shown in Figures 6 and 7 where the main panel 38 of the window is provided with celluloid or like thickening strips 39 and a channel shaped metal member 40 embraces the strips 39 and has inturned edges 41 to engage under the edges of the strips 39. The metal or like channel 40 is prevented from sliding off in an endwise direction by a single rivet 42 passing through the channel 40, the strips 39 and the main panel 38. The employment of a single rivet either at one end or in the centre permits of the differential expansion of the metal or like channel 40 and the window 38 with its thickening strips 39.

What we claim then is:—

1. A transparent panel applicable as a sliding window comprising a sheet of flexible transparent celluloid, independent portions of celluloid applied to two of its opposite edges, means for securing said strips, independent strips of celluloid applied to its two remaining edges and secured thereto, and metal strips freely associated with said portions.

2. A transparent panel comprising a sheet of flexible transparent material, a housing of the same material secured to at least one edge of the sheet and a stiffening member of metal freely mounted in said housing.

3. A transparent panel comprising a sheet of flexible transparent material, an independent loop of the same material secured to one edge of the sheet and a metal stiffening member freely mounted in said loop.

4. A transparent panel comprising a sheet of flexible transparent material, a channel shaped member of the same material secured to one edge thereof, a stiffening member mounted in said channel and a resilient buffer in the mouth of the channel and serving to retain the stiffening member in its place.

In witness whereof we affix our signatures.

HENRY GARNER.
JAMES PARKER GARNER.
